(57) **CLAIM**

The ornamental design for a support arm for a liquid crystal display, as shown and described.

DESCRIPTION

FIG. 1 is a perspective view of a support arm for a liquid crystal display, showing my new design;
FIG. 2 is a front elevational view thereof;
FIG. 3 is a rear elevational view thereof;
FIG. 4 is a left elevational view thereof;
FIG. 5 is a right elevational view thereof;
FIG. 6 is top plan view thereof; and
FIG. 7 is a bottom plan view thereof; and,
FIG. 8 is a perspective view showing an embodiment of the claimed design, wherein the broken lines are shown for illustrative purposes only and form no part of the claimed design.
